UNITED STATES PATENT OFFICE

EBEN RAY PACKER, OF NEW ROCHELLE, NEW YORK

GUARD-RAIL STRUCTURE

Application filed April 6, 1929. Serial No. 352,956.

The present invention relates to guard rails for railway track installations and consists of an improved guard rail construction comprising as a primary unit an integral guard rail casting adapted to be made of manganese steel and of a form to be rigidly secured in position upon the ties without the use of bolts, clamps or special securing devices. It is further of an improved form to permit of the use therewith, in accordance with an important feature of the present invention, of separable bracing members which may be economically made from commercial rolled steel and arranged to be operative to resist the severe lateral thrusts to which the head of the guard rail is subjected.

An important object of my present improvements is to effect a substantial economy in the completed structure, first, as the result of the employment of the reduced weight of the manganese or other high grade steel of which the guard rail proper is formed, with further savings incidental to the casting of a more uniform section, while offering additional economies incidental to the use of the separable bracing members.

The described and other valuable features of the present invention will be more fully understood by reference to the accompanying drawings wherein like reference numerals are applied to the corresponding parts in the several views.

In the drawings:

Figure 1 is a plan view of a guard rail made in accordance with the present invention.

Figure 2 is a view thereof in side elevation.

Figure 3 is a vertical cross sectional view taken on the line 3—3 of Figure 1.

Figure 4 is a vertical cross sectional view of the guard rail taken on the line 4—4 of Figure 1.

In the approved embodiment of the features of my invention as here shown, the guard rail proper is made of an integral casting and desirably of manganese steel, composed of a base portion 1 having laterally extended tie plate extensions 2, an upright web portion 3, a head portion 4 and at the extremities thereof the foot guard portions 5—5.

The head portion 4 of the guard rail has its inner wheel engaging surface curved outwardly at the end portions 6—6 as an entry guide for the wheel flanges and is laterally widened for strengthening purposes and intermediate of the ties has an additional widening of convex curvature at 7—and at the point of greatest width is connected by vertical ribs 8 to a correspondingly arched or widened portion of the base 1. Also as best illustrated in Figures 3 and 4, the web portion 3 overlying the tie plates is vertically disposed and has its intermediate portions between the ties, outwardly arched or angularly disposed, as shown in Figure 4 to obtain a bracing effect. The integral tie plate extensions 2 are arranged to underlie the base of the track rail 10, and at their outer projecting end portions are provided with staggered spike apertures 11 and additional spike apertures 12. The foot guard members 5, as shown, are formed with a horizontal wall suitably cored out for reduction in weight and provided with an inclined end wall 14.

In accordance with the important feature of the present invention, the inner side of the guard rail head is formed with recesses 15 in its under portion, positioned with relation to the ties. Fitted to said recesses there are provided separable bracing members 16, inwardly and downwardly inclined, and having angularly disposed toe portions 17 provided with the spike apertures 18 for spiking to the ties. The provision of the separable bracing members 16 which may be desirably formed of standard rolled steel, as commercially obtainable, allows of inexpensively providing for adequate bracing of the guard rail against the severe lateral thrusts and thereby opposes the lateral thrusts tending to tilt or turn over the guard rail section.

As will be appreciated, the employment of the separable braces economically allows providing bracing members extended laterally to a substantial degree, so that the bracing members will function to resist the lateral thrusts substantially or entirely under compression.

As best shown in Figure 2, the recesses 15 are desirably slightly elongated with rela-

tion to the width of the bracing members, thereby allowing a limited longitudinal adjustability of the bracing members, which offers the advantage of slightly shifting the position of the braces upon the ties for re-spiking when occasion occurs.

My improved guard rail structure accordingly possesses the important advantages of an integral manganese guard rail, while eliminating the excessive costs incidental to the casting of the inner bracing members as an integral part of the guard rail proper.

As will be readily understood, the casting of the inner bracing members integrally incurs considerable expense incident to the use of cores in the preparation of the moulds and further, by reason of the irregular enlargement of the section, results in a relatively large percentage of defective castings as commercially made. In addition thereto, by my employment of the separable bracing members of commercial or standard rolled section, there is a very substantial economy in the cost of material, while as aforesaid, the bracing members may be laterally extended to a larger degree to obtain a better bracing effect.

While I have shown and described an approved embodiment of the features of the present invention, it will be understood that varied modifications may be made therein without departing from the scope of the invention as defined in the appended claims.

As illustrative thereof, it will be understood that while the bracing members may be installed as separate members fitted within the recesses 15, the same may be readily united to the guard rail by welding of the upper ends of the members to the guard rail head if desired.

Having described my invention, I claim:

1. A guard rail structure comprising a guard rail member formed of an integral casting having a head member formed with its end portions inwardly flared, a web portion and a base portion, said head member being formed on its inner side with recesses and separable bracing members for the guard rail member having their upper ends fitted within said head recesses and having their lower inner ends bearing upon the ties.

2. A guard rail structure comprising a guard rail member formed of an integral casting of manganese steel having a head member formed with its end portions inwardly flared, a web portion and a base portion, said head member being formed on its under side with recesses and separable bracing members for the guard rail member having their upper ends fitted within the head recesses and having their lower, inner ends bearing upon the ties and said head recesses being longer than the width of the bracing members to allow of adjustably positioning the braces with respect to the ties.

3. A guard rail structure comprising a guard rail member formed of an integral casting of manganese steel having a head member having its end portions inwardly flared, a web portion, a base portion provided with tie plate extensions positioned to underlie the track rail and foot guard portions positioned at the ends thereof, said head member being formed on its inner side recesses and separable bracing members for the guard rail member having their upper ends fitted within said head recesses and having their lower inner ends bearing upon the ties, said head recesses being longer than the width of the bracing members to allow of adjustably positioning the braces with respect to the ties and said bracing members being formed of standard flat rolled steel section and apertured for spiking to the ties.

4. A guard rail structure comprising a guard rail member formed of an integral casting of manganese steel having a head member formed with its end portions inwardly flared, a web portion and a base portion and independently formed bracing members for the guard rail member having their outer ends fitted to recesses in the head member and their inner ends bearing upon the ties and means for securing the bracing members in position, said bracing members being formed of standard rolled steel section.

Signed at New York city, in the county of New York and State of New York, this 4th day of April A. D. 1929.
